US00D472264S

(12) **United States Design Patent** (10) Patent No.: **US D472,264 S**
(45) Date of Patent: **** Mar. 25, 2003**

(54) **EYEGLASSES**

(75) Inventor: **Henry Welling Lane**, San Luis Obispo, CA (US)

(73) Assignee: **Dioptics Medical Products, Inc.**, San Luis Obispo, CA (US)

(**) Term: **14 Years**

(21) Appl. No.: **29/135,900**

(22) Filed: **Jan. 19, 2001**

Related U.S. Application Data

(63) Continuation-in-part of application No. 29/135,899, filed on Jan. 19, 2001, now Pat. No. Des. 448,398, which is a continuation-in-part of application No. 29/135,903, filed on Jan. 19, 2001, now Pat. No. Des. 447,505, which is a continuation-in-part of application No. 29/135,904, filed on Jan. 19, 2001, now Pat. No. Des. 447,506, which is a continuation-in-part of application No. 29/135,888, filed on Jan. 19, 2001.
